UNITED STATES PATENT OFFICE.

HAROLD EDWARD SHERWIN HOLT, OF FARNBOROUGH, ENGLAND.

RAZOR.

1,018,420.

Specification of Letters Patent.

Patented Feb. 27, 1912.

Application filed April 25, 1910. Serial No. 557,526.

To all whom it may concern:

Be it known that I, HAROLD EDWARD SHERWIN HOLT, a subject of the King of Great Britain and Ireland, residing at The 5 Grange, Farnborough, Hants, England, have invented certain new and useful Improvements in Razors, of which the following is a specification.

This invention for improvements in or 10 connected with razors has for its object to provide a blade holder for a razor in which a separate thin flexible blade or a rigid blade may be detachably secured and held either for stropping or shaving in the same manner 15 as razors of the ordinary non-safety type.

A further object of the invention is to provide a holder for use in stropping safety razor blades.

According to this invention I provide a 20 rigid back or frame adapted to be pivoted in a handle after the manner of an ordinary razor blade and to receive a blade and hold it by end tension or end pressure. The rigid back or frame has a forward projection 25 for engaging one end of the blade and carries a pivoted folding part or lever having a long arm and a short arm or projection at an angle to the long arm for engaging the other end of the blade and arranged when 30 folded and secured to put the blade under tension or pressure. The lever is secured in the folded position by a suitable catch thereon engaging an opening in the back.

Another form comprises a bow-shaped 35 holder proper with a projection arranged to engage an opening in one end of the blade and an adjustable rod or stem mounted to slide in a hollow handle secured to the bow shaped part and engaging the other end of 40 the blade. In a practical form of construction the stem is made in two parts one of which is provided with a milled head for turning and the other arranged to screw into it but not to rotate.

45 In the accompanying sheet of illustrative drawings Figure 1 is a side elevation on an enlarged scale of a razor constructed according to this invention, the detached blade being shown in dotted lines. Fig. 2 is a 50 similar view to Fig. 1, illustrating how one part of the frame or blade holder can be moved to allow of the insertion or removal of the blade. Fig. 2^a is a sectional view on

lines 2^a—2^a of Fig. 2. Fig. 3 is a side elevation partly in section of a modified form 55 of blade holder for use either in stropping or shaving.

Referring to Figs. 1 and 2 the frame or blade holder *a* is pivoted to fold in a razor handle *a'* of the ordinary type, and consists 60 of a rigid back *a²* with an integral fixed projection or arm *b* provided with a stud *c* for engaging one end of the blade *d* and a movable arm *b'* provided with a stud *c'* for engaging the other end of the blade *d*. The 65 movable arm *b'* forms part of a folding angle lever *e* pivotally connected at *f* with the rigid back *a²*, and provided at the opposite end with a catch *g* which in the folded position enters a slot *h* in the rigid back 70 *a²* as shown in Fig. 1. To facilitate its release the catch has an extension *g'* thereon to which pressure may be applied with the finger. In the example shown the blade *d* which has suitable openings near its ends 75 for the engagement of the studs *c c'* on the frame or holder, is held in position on the studs by the tension exerted through the angle lever *e* when in the folded position. When not in use the blade may be folded 80 into the handle *a'* and thereby protected from injury.

In the modified form of construction shown in Fig. 3 a bow shaped holder or back *a²* is fixed on a suitable handle *a'*, 85 bored longitudinally to receive a rod or stem formed in two parts *i i'*. The part *i* is mounted to rotate and has a milled head *j* at one end and at the other end an internally screw-threaded opening for the reception of 90 a screwed pin *k* formed on the other part *i'* of the stem which is arranged to slide but not rotate in the handle. The blade *d* is held on studs or projections *c c'* formed respectively on the stem part *i'* and the bow 95 shaped back *a²*. Tension or pressure is applied to the blade to retain it on the studs *c c'* by turning the milled head *j*.

It will be seen that the holders described may be used to hold a blade of the safety 100 type either for stropping or shaving, and that the blades are readily reversible or renewable.

What I claim and desire to secure by Letters Patent is:—

A razor comprising in combination, a

blade, holding means therefor composed of a main longitudinal member having a lateral blade holding portion projecting therefrom and also having a locking opening, an element hinged to one end of said member and having one end bent for connection with the blade, the body of said element extending along said main member and hav-

ing on its other end a shoulder or lug to enter said opening. 10

In testimony whereof I have affixed my signature, in presence of two witnesses.

HAROLD EDWARD SHERWIN HOLT.
